UNITED STATES PATENT OFFICE.

BENJAMIN H. SMITH, OF SWISSVALE, PENNSYLVANIA, ASSIGNOR TO WESTINGHOUSE ELECTRIC & MANUFACTURING COMPANY, A CORPORATION OF PENNSYLVANIA.

REGULATOR SYSTEM.

Continuation of application Serial No. 579,148, filed August 2, 1922. This application filed January 22, 1924. Serial No. 687,730.

This application is a continuation of application Serial No. 579,148, filed August 2, 1922, as to all matter contained in that application.

5 My invention relates to regulator systems and it has special relation to load-regulating systems. More specifically stated, the invention relates to means for automatically regulating the feed of granular material to 10 apparatus in which it is to be treated, and its primary object is to provide means for regulating the feed to an apparatus in response to load changes thereupon, and operating at a certain time interval after the 15 load changes occur.

Another object of my invention is to provide a load-regulating apparatus of the above-indicated character that shall comprise a continuously operated mill motor, a 20 motor-operated feeding device cooperating therewith and means for controlling the feed motor in accordance with variations in load upon the mill motor. The feed-motor controlling means operates with a certain 25 time element, whereby the action thereof is delayed so that the mill motor may have opportunity to accommodate itself to one regulating adjustment before another is made.

Briefly, the present invention is adapted 30 for use in a ball mill for crushing ores and that comprises a rotary ball mill proper, a feed mechanism therefor, and a motor-operated classifier adapted to receive the crushed ore.

35 Any control of the feed of the ore to the ball mill in accordance with the load upon the classifier must include a time element device in order that the increased or decreased load upon the ball mill will have 40 an opportunity to correspondingly affect the load upon the classifier. For the most efficient operation, the ball mill should be maintained at about six-tenths its capacity. It has been found that the load upon the 45 classifier motor is the only accurate measure of the load upon the ball mill.

50 My invention will be best understood by reference to the accompanying drawing, wherein the single figure is a diagrammatic illustration of circuits and apparatus embodying my invention.

Referring to the drawing, a motor-driven ball mill 1 discharges crushed ore on a traveling belt conveyor 2, which feeds the

ore to a classifier 3. The properly crushed 55 ore is discharged from the classifier 3 on a traveling belt conveyor 4, and material requiring further crushing is discharged on elevator 5 and returns by means of the belt conveyor 6 to the ball mill. A classifier motor 7, having a rotor 8 and a stator 9, operates the classifier 3 by means of a shaft 10 and the illustrated cooperating mechanism.

The material to be crushed is fed through 60 hopper 12 on the traveling conveyor 6 to 65 the mill 1. The discharge of material from the hopper 12 is regulated by a gate 13 through worm gearing 14, which is driven by the feed motor 15.

The direction of rotation of the feed motor 15 is controlled by means of the reversing 70 switches 16 and 17; these switches being provided with electromagnetic coils 18 and 19, which are energized in accordance with the operation of a thermal-watt relay 21. 75

The thermal-watt relay 21 comprises two bimetallic heat-responsive elements 22 and 23 mounted upon a shaft 32. The heat-responsive elements are coiled in opposite directions to each other so as to have a differential action, the one element opposing the other upon being heated. Four heating elements 24, 25, 26 and 27 are provided; the first two named being associated with the 80 heat-responsive element 22 and the last two 85 named being associated with the heat-responsive element 23.

The two heating units 24 and 27 are connected in parallel circuit relation, one end of this parallel circuit being connected to 90 one terminal of the secondary coil of a current transformer 28. The parallel circuit includes also the secondary coil of a voltage transformer 31, the primary coil of which is connected to the source of power that energizes 95 the classifier motor 7. From the middle point of the secondary coil of the transformer 31, a tap is led out which is connected to the two heating elements 25 and 26. These heating elements are connected 100 in parallel circuit relation and to the terminals of the secondary coil of a voltage transformer 29, the primary coil of which is connected to be energized in accordance with the voltage applied to the 105 feed motor 15. From the middle point of the secondary coil of the transformer 29 a tap is led out, which connects to the re-

maining terminal of the secondary coil of the current transformer 28.

The shaft 32, which is actuated in accordance with the heating of the two elements 22 and 23, operates a lever 33 carrying contact members 34, which are adapted to engage stationary contact members 35 and 36 to complete circuits through the reversing switch-controlling magnets 18 and 19, respectively.

A manually operated switch 38 is provided to control the operation of the feed motor 15 when manual control is desired. Should the contact segments 41, 42 and 43 be moved to the left, contact segment 41 would then engage the two upper contact fingers 39, thus closing the circuit through battery 37 and electromagnet 19. Again, should the contact segments be moved to the right, from the position shown, contact segment 42 would engage the two lower contact fingers 39 and close the circuit through electromagnet 18. In the mid-position, in which it is shown in the drawing, the contact segment 44 engages the contact fingers 43, thus connecting the contact members 34, carried by the lever 33, to the battery 37 and permitting control of electromagnets 18 and 19 by the operation of thermal-watt relay 21.

The operation of the device when utilizing automatic control is as follows: The ore to be crushed is fed to the ball-mill crusher by means of the feed mechanism, indicated generally at 11. The amount of ore fed to the ball mill 1, and then to the classifier 3, is controlled in accordance with the position of the motor-operated gate 13. When the mill is first started up, there will be substantially no load on the classifier motor 7 and hence the energization of the thermal-watt relay 21 will be correspondingly weak. The regulator mechanism is adjusted so that its contact members will be so brought into engagement as to energize the proper reversing switch to operate the feed motor 15 to open the gate 13. Since an appreciable time is required in passing the ore through the ball mill to the classifier, it is important that the engaged contact members should not be separated until the ore reaches the classifier, and the classifier becomes partially loaded.

The bimetallic heat-responsive element 23 is heated in accordance with the watts consumed by the classifier motor 7, and the opposing heat-responsive element 22 is heated in accordance with the energization of the gate motor 15, voltage being applied to the transformer 29 at the same time that it is applied to the motor 15.

Since the element 22 is heated only when the gate motor 15 is energized, and this element opposes the rotation of the shaft 32 as effected by the element 23, the heating of element 22 acts as an anti-hunting device and separates the contact members that are

controlled by the lever 33 earlier than they would otherwise be separated. This anti-hunting is of importance, since it prevents surges in load upon the ball mill and maintains the mill at its maximum efficiency.

70

The regulator mechanism may be so adjusted that the gate 13 will be only partially open at the time the heat-responsive elements 22 and 23 become heated in the proper proportion to open the contact members controlling the feed motor 15. In order that the full effect of changing the setting of the gate 13, controlling the ore admitted to the crusher, may be felt by the change in load upon the classifier motor, it is necessary to have a time element in the operation of the regulator mechanism so that it will not repeat its function, after one operation, until sufficient time has passed for the ore to reach the classifier. This time lag is obtained by adjusting the bimetallic elements 22 and 23, so that they require a definite amount of heating and cooling to operate the watt-relay contact members.

75

80

85

After the watt-relay contact members are closed, there is a certain time interval before they will open, this time interval depending upon the rate of heating of the heat-responsive elements. Also, after the watt-relay contact members are separated, there will be a certain time interval, during which the heat-responsive elements are cooling, before the contact members may again close.

90

95

After this time interval has passed, the contact members will be again closed to operate the reversing switches controlling the motor 15 so as to further open the gate 13. This operation of the gate 13 may be repeated two or three times until a permanent position of the gate, corresponding to that of normal load upon the ball mill, is reached. Any subsequent operation of the regulator mechanism in the one direction or the other will be initiated by reason of variations in load upon the ball mill, as indicated by the load on the classifier motor.

100

105

110

Modifications in the system, and in the arrangement and location of parts may be made within the spirit and scope of my invention, and such modifications are intended to be covered by the appended claims.

115

I claim as my invention:

1. In a regulator system, the combination with a main motor, apparatus operated thereby, feeding mechanism for said apparatus, a motor operating said feeding mechanism, and reversing switches for said feed motor, of means energized in accordance with the operation of said motors and adapted to control the operation of said feed motor intermittently.

120

2. In a regulator system, the combination with a motor, apparatus operated thereby, feeding mechanism for said apparatus, a motor operating said feeding mechanism

125

130

and reversing switches for said feed motor, of means for operating said reversing switches for a predetermined period, interrupting the operation of said reversing switches for a predetermined period, and repeating the operation upon the occurrence of variations in load upon the apparatus motor.

3. In a regulator system, the combination with a motor, the load upon which is to be kept substantially constant, of means for controlling the load upon said motor, said control means having a time element in the operation thereof.

4. The combination with a device, the load upon which is to be kept substantially constant, a driving motor therefor, means for controlling such load and an operating motor therefor, of means for governing the operation of said operating motor, said means functioning in accordance with certain operating characteristics of said motors and thereafter introducing a time element into the subsequent operations thereof.

5. In a load-regulator system, the combination with a motor, apparatus operated thereby, feed mechanism cooperating with said apparatus, and a motor operating said feed mechanism, of regulating means controlled in accordance with the load upon said apparatus motor and adapted to control said feed motor, said regulating means comprising a thermal-responsive element and heating means therefor energized in accordance with the operation of said motors.

35 6. In a load-regulator system, the combination with a motor, apparatus operated thereby and adapted to be loaded, feed mechanism cooperating with said apparatus, and a motor operating said feed mechanism, of regulating means controlled in accordance with the load upon said apparatus motor and adapted to control said feed motor, said regulating means comprising a thermal element and heating means therefor energized from said motors and adapted to have a delayed action, whereby a predetermined time element will be introduced into the operation of said regulating means.

7. In a load-regulator system, the combination with a motor, apparatus operated thereby and adapted to be loaded, feed mechanism cooperating with said apparatus, and a motor operating said feed mechanism, of thermal regulating means controlled in accordance with the load upon said apparatus motor and adapted to control said feed motor, said means including differentially operative bimetallic members, heating coils therefor respectively energized from said feed motor and said apparatus motor, and contact mechanism governed thereby.

8. In a regulator system, the combination with a mill motor and a feed motor, of means for controlling said feed motor comprising differentially related elements ener-

gized in accordance with the loads on said mill and feed motors.

9. In a regulator system, the combination with a mill motor and a feed motor, of means for controlling said feed motor comprising differentially related thermal elements energized in accordance with the load on said mill and feed motors.

10. In a regulator system, the combination with a mill motor and a feed motor, of means for controlling said feed motor comprising differentially related thermal elements, and means for heating said thermal elements in accordance with the loads on said mill and feed motors.

11. In a regulator system, the combination with a mill motor and a feed motor, of means for controlling said feed motor comprising differentially related wattmeter elements, and means for energizing said wattmeter elements in accordance with the loads on said mill and feed motors.

12. In a regulator system, the combination with a mill motor and a feed motor, of means for controlling said feed motor comprising differentially related thermal elements, and means for heating said thermal elements in accordance with the loads on said mill and feed motors, said last named means being adapted to cause the regulating system to operate intermittently.

13. In a regulator system, the combination with a mill motor and a feed motor, of means for controlling said feed motor comprising differentially related wattmeter elements, and means for energizing said wattmeter elements in accordance with the loads on said mill and feed motors, said last named means being adapted to cause the regulating system to operate intermittently.

14. In combination, a motor-driven ball crushing mill, a motor-driven classifying mill associated therewith, and a motor-driven feeding mechanism therefor, means for controlling the feed motor in accordance with the load upon the classifier motor.

15. In combination, a motor driven ball crushing mill, a motor-driven classifying mill for classifying the material discharged from the crushing mill, means for regulating the load upon the ball-mill motor in accordance with the load upon the classifier motor.

16. In combination, a motor-driven ball crushing mill, a classifying mill for classifying the material discharged from the crushing mill, a classifier motor therefor, feeding mechanism for controlling the supply of material to said crushing mill, and a feed motor therefor, means actuated in accordance with the load upon said classifier motor for controlling said feed motor.

In testimony whereof, I have hereunto subscribed my name this 8th day of January 1924.

BENJAMIN H. SMITH.
